UNITED STATES PATENT OFFICE.

AZEL GAY, OF ROCHESTER, NEW YORK, ASSIGNOR TO BARCALO MANUFACTURING COMPANY, OF BUFFALO, NEW YORK.

CRIB-BED.

1,179,714.

Specification of Letters Patent. Patented Apr. 18, 1916.

Application filed September 15, 1913. Serial No. 789,755.

To all whom it may concern:

Be it known that I, AZEL GAY, of Rochester, in the county of Monroe and State of New York, have invented certain new and useful Improvements in Crib-Beds; and I do hereby declare the following to be a full, clear, and exact description of the same, reference being had to the accompanying drawings, forming a part of this specification, and to the reference-numerals marked thereon.

The present invention relates to beds and more particularly to crib beds of the type in which the sides are adapted to be raised and lowered to facilitate handling the child or infant and making the bed and later to prevent the occupant from falling or climbing out and it has for its object to provide a simple, efficient, and easily manipulated means for, preferably automatically locking or supporting the side or sides in their raised or lowered positions and also at intermediate points if desired.

To these and other ends the invention consists in certain improvements and combinations of parts all as will be hereinafter more fully described, the novel features being pointed out in the claims at the end of the specification.

In the drawings: Figure 1 is an elevation of a portion of a crib bed comprising a part of the side frame and an adjacent portion of the bed frame, the one being supported on the other by a device constructed in accordance with and illustrating one embodiment of my invention, Fig. 2 is a top plan view of the end portion of the top bar of the side frame, Fig. 3 is a vertical section taken substantially on the line *b*—*b* of Fig. 1, and Fig. 4 is a horizontal section taken substantially on the line *a*—*a* of Fig. 1.

Similar reference numerals in the several figures indicate the same parts.

It will be understood that one locking device constructed as hereinafter described is to be provided at each end of the side frame of the bed but as one is merely a duplication of the other a description of one will suffice for both. Referring therefore more particularly to the drawings, 1 indicates the head or foot post of the bed and 2 the side frame, the invention being illustrated in the present instance in connection with an iron bed. A guide rod 3 extends longi-

tudinally of the post 1 offset therefrom and supported by brackets at top and bottom such as that shown at 4. The top and bottom bars 6 of the side frame 2 terminate in eyes 5 which slide freely on the guide rods 3 as the side frame is moved between the raised and lowered positions.

The top bar 6 is preferably reduced adjacent to the eye 5 as at 7 providing a shoulder 8 and straddling this portion of the bar is a yoke shaped hanger 9 which in assembling may be slipped over the eye 5 while held in the plane thereof and then rotated into a vertical position against the shoulder 8 and behind a lateral projection 10 that may be struck up from the bar, as shown, whereby longitudinal displacement of the yoke is prevented. Pivotally supported between the arms of the yoke 9 on a rivet or pin 11, subsequently attached is a lever 12 one arm of which extends toward the body of the frame just beneath the bar 6 to constitute an operating handle or finger portion 13 while the other arm 14 is pivoted at 15 to a sliding clutch element 16 preferably in the form of a yoke straddling the guide rod 3 and receiving the arm 14 of the lever between its end portions. The extremity of the lever arm 14 is preferably rounded as at 17 and constitutes a clutch face that engages the rod 3 in opposition to the yoke 16 when the lever is rotated to one position and which recedes from such engagement also freeing the yoke 16 when moved in the other direction. The gripping movement of the lever is such that its sliding engagement with the rod 3 tends to render it operative as a friction clutch in connection with the yoke 16 so that if left to itself it will automatically lock and support the side frame at any given position of adjustment until released by what in the present instance would be upward pressure on the finger portion 13 of the lever.

It will be noted from the drawings that the side frame 2 through the medium of the yoke or hanger 9 is supported directly on the lever at the pivotal point 11 and communicates to the lever a pressure such as will rotate it or tend to rotate it on its pivotal connection 15 with the other clutch element 16 into locking position. In order to insure the engagement of the clutches, however, when the operator is still retaining the weight of

the side frame, I provide a spring 18 that may be turned about a pin 19 between the arms of the yoke 9 which spring bears against the lever to the same effect as the weight of the frame. The spring may be retained in position by a spur 20 struck out from one of the arms of the yoke 9.

It is believed that the operation of the device need not be further described at any length, the operator simply lifting up on the finger portion 13 of the lever to release the clutch whenever the side frame is to be adjusted up or down or if the parts are suitably adjusted merely lifting on the side frame will cause the clutch to slip upwardly on the guide rod. Crib beds are so short that one person can easily release the clutch at each end of the side frame with his two hands and still be in a position to raise or lower its weight.

My device is of a simple nature easily constructed from stamped sheet metal parts and the locking element being of an automatic and frictional character the adjustments of the side frame are not limited to two positions but on the other hand any intermediate position may be as readily attained allowing it to be kept in a semi-raised position, for instance, when the child is very small and be gradually raised as the child gets older so that it is always as low as is safe and more convenient for leaning over the crib. Of course the pivotal connections 11 and 15 are made sufficiently loose or sufficient play of the parts is elsewhere provided to prevent binding as a result of the fact that the lever turns at two pivotal points.

I claim as my invention.

- 40 1. In a crib, the combination with a frame having upright guide rods, and a side frame movable on said guide rods between raised and lowered positions, of a friction clutch carried by the side frame and coöperating with said guide rod to hold the side frame at different positions of adjustment, said clutch comprising a member arranged to slide on said guide rod, and a lever pivoted to said sliding member to move relatively thereto to clamp the guide rod between said sliding member and lever or release the same, said lever being also pivotally connected to the side frame and supporting said sliding clutch member.
- 55 2. In a crib, the combination with a bed frame having an upright guide rod and a side frame movable up and down on said guide rod and having a horizontal top rod, of a friction clutch coöperating with said guide rod to hold the side frame at different positions of adjustment, said clutch comprising an operating lever and a strap which

straddles said top rod of the side frame and to which said lever is pivoted.

3. In a crib, the combination with a frame 65 having an upright guide rod and a side frame movable up and down on said guide rod, of a friction clutch coöperating with said guide rod to hold the side frame at different positions of adjustment, said clutch 70 comprising a lever and a strap which straddles and is adapted to slide on said guide rod and between the ends of which said lever is pivoted, said lever being pivotally supported on said side frame and supporting 75 said strap and being pivotally movable relative to the strap to grip and release said guide rod.

4. In a crib, the combination with a frame 80 having a guide rod, and a side frame movable on the guide rod between raised and lowered positions, of a friction clutch carried by the side frame and coöperating with the guide rod to hold the side frame at different positions of adjustment, said clutch 85 comprising a yoke straddling the guide rod and a lever pivoted between the arms of the yoke and having a gripping portion movable about said pivot toward and from the rod, an additional pivotal connection between the lever and the side frame by means 90 of which the lever is supported on the side frame, said lever supporting said yoke and being adapted to be operated on its pivotal connection with the side frame to release it 95 from the guide rod, and a spring normally operating to force the lever into locking engagement with the guide rod.

5. In a crib bed, the combination with a 100 bed frame having a vertical guide rod and a side frame movable on the guide rod between raised and lowered positions, and embodying a horizontal bar, of a friction clutch carried by the side frame and coöperating with the guide rod to hold the side frame at different positions of adjustment, said clutch 105 comprising a sliding member engaging on one side of the rod and a lever pivoted to the sliding member and having a gripping portion movable on said pivot as a center into and out of operative engagement with the other side of the rod, and a yoke arranged to straddle the bar on the side frame and between the arms of which the lever is also pivoted whereby the side frame is supported 110 on the lever in such manner that its weight tends to move the latter to gripping position, the lever being adapted to be operated on the pivot of the yoke to release it from the rod.
